O'Connell Law Firm

(57) **CLAIM**

We claim the ornamental design for a headset, as shown and described.

DESCRIPTION

FIG. 1 is a perspective view of a headset showing our design;
FIG. 2 is a rearward perspective view thereof;
FIG. 3 is a view in front elevation thereof;
FIG. 4 is a view in rear elevation thereof;
FIG. 5 is a view in right side elevation thereof;
FIG. 6 is a view in left side elevation thereof;
FIG. 7 is a top plan view thereof;
FIG. 8 is a bottom plan view thereof;
FIG. 9 is a perspective view of an alternative embodiment of the headset;
FIG. 10 is a rearward perspective view of the headset of FIG. 9;
FIG. 11 is a view in front elevation of the headset of FIG. 9;
FIG. 12 is a view in rear elevation of the headset of FIG. 9;
FIG. 13 is a view in right side elevation of the headset of FIG. 9;
FIG. 14 is a view in left side elevation of the headset of FIG. 9;
FIG. 15 is a top plan view of the headset of FIG. 9; and,
FIG. 16 is a bottom plan view of the headset of FIG. 9.
The broken lines are for illustrative purposes only and do not form a part of the claimed design.

1 Claim, 16 Drawing Sheets
